US00D434753S

United States Patent [19]

Druckenmiller et al.

[11] Patent Number: Des. 434,753

[45] Date of Patent: ** Dec. 5, 2000

[54] LIGHT EMITTING DIODE MODULE

[75] Inventors: **Stephen P. Druckenmiller**, Cumming, Ga.; **John D. Dent**, Claremont, Calif.; **Bradford J. Rogers**, Suwanee, Ga.; **Eric Tsang**, Rowland Heights, Calif.

[73] Assignee: **Scientific-Atlanta, Inc.**, Norcross, Ga.

[**] Term: 14 Years

[21] Appl. No.: 29/093,964

[22] Filed: Sep. 21, 1998

[51] LOC (7) Cl. 14-03

[52] U.S. Cl. D14/239

[57] CLAIM

The ornamental design for a light emitting diode module, as shown and described.

DESCRIPTION

FIG. 1 is a top front left perspective view of a light emitting diode module showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view; and,

FIG. 7 is a rear elevational view thereof.
